(57) CLAIM

The ornamental design for a playpen, as shown and described.

DESCRIPTION

FIG. 1 is a perspective view of a front, top, and left side of an ornamental design for a playpen;

FIG. 2 is a perspective view of a rear, top, and right side of the playpen of FIG. 1;

FIG. 3 is a front elevational view of the playpen of FIG. 1; FIG. 4 is a rear elevational view of the playpen of FIG. 1; FIG. 5 is a right side elevational view of the playpen of FIG. 1;

FIG. 6 is a left side elevational view of the playpen of FIG. 1; and,

FIG. 7 is a top plan view of the playpen of FIG. 1.

The short dashed horizontal and vertical lines on mesh and stippled surfaces depict stitching and form a part of the claimed design. All other broken lines including the poles and straps form no part of the claim. The stippling in the figures illustrates a contrast to other claimed portions of the figures. The dense stippling represents a first appearance and the loose stippling represents a second appearance, different than the first appearance.
